Attorney

UNITED STATES PATENT OFFICE.

EUGENE F. BEEBE, OF MINNEAPOLIS, MINNESOTA.

WASHING MACHINE.

Application filed November 19, 1921. Serial No. 516,361.

To all whom it may concern:

Be it known that I, EUGENE F. BEEBE, a citizen of the United States, residing at Minneapolis, in the county of Hennepin and 5 State of Minnesota, have invented certain new and useful Improvements in Washing Machines, of which the following is a specification, reference being had to the accompanying drawings.

10 This invention relates to washing machines, and particularly to washing machines of the character described and illustrated in Patent #1,135,565 granted to me on April 13, 1915, the general object of my 15 invention being to simplify and improve the washing machine illustrated in this patent.

More specifically, one of the objects of the present invention is to improve upon the means whereby the pounders or plungers 20 are cushioned in their stroke.

A further object in this connection is to so form the means for transmitting motion to these pounders or plungers that while one plunger is being positively raised to 25 a height sufficient to permit the plunger cup on the lower end of the plunger being raised above the water line to receive air, the other plunger shall be lowered to an extent permitted by the amount of clothes 30 in the tub, the downward movement of the last named plunger, however, which is limited by the amount of clothes in the tub, not preventing the full rocking of the actuating rock shaft.

35 A further object is to so construct the plungers and plunger operating mechanism that less mechanism will be disposed above the cover of the tub than is the case in my Patent #1,135,565 before referred to, so 40 that these parts may be enclosed in a housing.

Still another object is to provide means whereby the plunger actuating mechanism which is mounted upon the cover of the 45 tub becomes automatically disconnected from the driving mechanism when the cover of the tub is raised.

Other objects have to do with the details of construction and arrangement of these 50 parts, as will be hereafter more fully described.

My invention is illustrated in the accompanying drawings, wherein:—

Figure 1 is a perspective view of a washing machine constructed in accordance with 55 my invention;

Figure 2 is an elevation looking at one end of the machine, showing the tub and cover in section;

Figure 3 is a fragmentary perspective 60 view of the cover and a portion of the plunger actuating mechanism;

Figure 4 is a sectional view of the cover and the actuating mechanism;

Referring to the drawings, it will be 65 seen that the tub 10 is mounted upon a suitable supporting frame which includes the upwardly convergent legs 11. A cross bar 12 extends across the lower portion of the frame and beneath the tub 10, which 70 tub 10 is supported on a central bearing 13. The tub is provided on its under side with a ratchet ring 14 which is engaged by a dog 15 mounted on a pivot arm 16. A crank 17 is secured on a horizontal shaft 75 18, this crank being connected to the arm 16 by a link 19. The rotation of the shaft 18 will thus cause the constant intermittent rotation of the tub when the machine is in 80 operation. These parts are fully shown in 85 my prior patent heretofore referred to.

The shaft 18 is mounted in suitable bearings and carries upon it a gear wheel 20 mounted within a housing 21, this gear wheel being engaged by a pinion 22 within 90 a housing 23. This pinion is mounted upon a shaft 24 carrying upon it the band wheel 25. A band passes over this wheel 25 to a driving wheel 26 mounted upon a motor driven shaft 27. The motor used 95 for driving this machine may be an electric motor, gasoline engine or any other suitable engine of this character, but I do not wish to be limited to the use of a motor as the machine may be operated by hand power, as illustrated in my prior patent.

The cover of the machine is designated 28, and mounted upon the upper ends of the converging legs 11 is a bracket casting 29 formed to provide a bearing 30 and upwardly extending ears 31. Attached to the cover is a hollow arm 32 which is open at

its ends and at one end is provided with the upwardly and outwardly extending ears 33 which are pivoted by a transverse bolt 34 to the ears 31. This arm 32 carries upon it the upright 35, to whose upper end is pivoted the latch rod 36. The free end of this rod is received in a recess 37 in the upper end of an upright 39 formed integral with and extending upward from the bearing 30. When this arm 36 is in the recess 37, the cover 28 is held from any lifting movement. When it is desired to lift the cover, the arm 36 is detached from the recess 37 and then the arm 32 with the cover may be raised.

The arm 32 at its inner end opens into a housing 40, within which the plunger operating mechanism is disposed. The plunger operating mechanism comprises a shaft section 42 carried in suitable bearings within the arm 32, this shaft section projecting beyond the arm 32 and into the housing 40 and carrying upon its end the yoke 43. This shaft 42 is a rock shaft. The yoke 43 is an approximately triangular member and oscillates with the rock shaft 42 and has at its outer upper corners the inwardly projecting pins 44.

Loosely mounted upon the end of shaft 42 are two angularly bent arms 45 and 46. These arms are independent of each other. The outer end of the arm 45 is connected to a plunger rod 47, while the other end of the arm 46 is also pivotally connected to a like plunger rod 47. The lower ends of these plunger rods carry the inverted cups or plungers 48. Projecting downward from or through the cover 28 is a bracket 49 carrying a bolt upon which is pivoted the two arms or levers 50. The ends of the arms are forked or bifurcated and embrace the rods 47 and are pivoted thereto at 51. Thus a parallel movement is secured for the rods 47.

Extending upward from each of the arms 45 and 46 are integral eyes 52, through which eyes passes a rod 53 having cotter pins or like detachable stops 54 at its ends and surrounding this rod 53 and disposed between the eyes 52 is a coil compression spring 55. With this construction, when the right hand side of the yoke 43 in Figure 2 moves upward, the pin 44 will strike the arm 45 and lift this arm upward, exerting a camming action against this arm. The upward and inward motion of the inner portion of the arm 45 will be transmitted by the corresponding eye 52 to the spring 55, thence to the eye 52 on the arm 46 and the arm 46 will be correspondingly depressed. If, however, an accumulation of clothes within the tub prevents the full downward movement of the plunger attached to the arm 46, the arm 45 will continue to move but

spring 55 will become compressed as soon as the plunger 48 of arm 46 has reached a point where it cannot move down further. Of course, a like operation is true upon a reverse movement of the yoke, the arm 46 being in this case lifted and the arm 45 depressed to the full extent which is permitted by the clothes within the tub.

In order to provide means whereby when the cover 28 is lifted the plunger operating mechanism shall be disconnected from the power, I mount within the bearing 30 a shaft section 56 which at its end carries an arm 57 connected by a pitman 58 to a crank 59 on shaft 18. Thus as the shaft 18 is revolved, the shaft section 56 will be oscillated. This shaft section carries upon it a sliding clutch member 60 which is keyed or otherwise connected to the shaft 56 to oscillate therewith, this clutch member being urged outward by means of the spring 61 disposed between the clutch member and the bearing for the shaft 56. The shaft 42 at its end is formed to provide a clutch face 62 which is adapted to engage with the clutch face of the clutch 60. It will now be obvious that when the cover is raised, the clutch face of the shaft 42 will disengage from the clutch 60, and that when the cover is lowered the shaft 42 will press inward on the clutch 60 against the action of spring 61 and the shaft section 42 and shaft section 56 will be oscillated together. The spring 61 acts to secure a thoroughly good clutch connection between the two clutch faces.

For the purpose of disconnecting the plunger operating mechanism from the driving mechanism when it is desired to operate the wringer, a clutch (not shown) is disposed in the housing 22 and operated by means of a rod 63 which is connected to a handle 64. The particular means whereby this connection is accomplished, however, forms no part of my present invention. I have not illustrated any wringer or any means for supporting the same, but it will be understood that a wringer is to be used in connection with the machine.

The advantages of the construction which has been described are as follows: It is necessary in the operation of the machine that the plungers should each be lifted so that they will clear the surface of the water so that air may enter the plungers and be forced into the clothes upon the downward movement of the plunger. Therefore, it is necessary that the plungers should secure a full upward movement, whereas the downward movement of the plungers is, of course, limited by the amount of clothes within the tub. This variable stroke is secured by the mechanism which I have described, whereby each plunger is alternately fully lifted but is depressed to an extent limited by the

amount of clothes in the tub without, however, in any way impeding the full oscillation of the shaft sections 56 and 42. Furthermore, it will be seen that by disposing 5 the second set of arms 50 below the cover 28, I reduce the height of the mechanism above the cover so that I may enclose this mechanism within the housing 40.

Furthermore, in comparison with the construction illustrated in Patent 1,135,565, it 10 will be seen that I have simplified this construction by using only one spring 52 instead of the four springs which were necessary in the construction illustrated in said 15 patent.

Of course, the general operation of the washing machine is obvious. The cups or plungers working up and down alternately, by reason of the spring 55, are adjusted automatically to a heavy or light load, which 20 gives the desired pressure on all thicknesses of clothes in the tub. Soapy water is forced down through the clothes by the pressure of the air compressed within the cup-shaped 25 plungers 48 and vacuum or suction is caused by the upward movement of the plungers, which draws the clothes up from the bottom of the tub. The tub moves round its axis at each movement of the plungers, thus causing 30 the plungers to act in a new position at each stroke.

I claim:—

1. In a washing machine, a tub, an oscillatable shaft, a pair of independent, pivotally mounted arms, plungers pivotally connected to the ends of the arms and extending into the tub, a compression spring operatively mounted between the arms and adapted to transmit motion from one arm 40 to the other, and means carried by the shaft for alternately lifting one arm or the other.

2. In a washing machine, a tub, an oscillatable driving shaft, a pair of arms loosely mounted upon said shaft for free oscillation relative thereto and to each other, plungers connected to the ends of said arms and extending into the tub, a compression spring operatively carried by said arms and disposed between the same and transmitting 50 power from one arm to the other, and means carried by the oscillating shaft for alternately engaging one or the other arm to lift it.

3. In a washing machine, a tub, a cover 55 therefor, an oscillatable, power driven shaft mounted upon the cover, a pair of arms loosely mounted upon the shaft and extending in opposite directions, a compression spring disposed between the arms and operatively carried thereby and adapted to transmit power from one arm to the other, plungers carried upon the extremities of the arms and extending through the cover of the machine, a bearing mounted upon the

under side of the cover, and connected rocker 65 arms mounted upon said bearing and connected at their extremities to the plungers.

4. In a washing machine, a tub, a cover therefor, an oscillatable driving shaft mounted upon the cover, a pair of oppositely extending arms loosely mounted upon the shaft for independent motion relative to each other, plungers connected to the extremities of said arms and extending through the cover, means connected to the shaft whereby as the shaft oscillates the arms may be alternately raised, and yielding means disposed between the arms transmitting power from one arm to the other. 70 75

5. In a washing machine, a tub, a cover 80 therefor, an oscillatable driving shaft mounted upon the cover, a pair of oppositely extending arms loosely mounted upon the shaft for independent motion relative to each other, plungers connected to the extremity 85 of said arms and extending through the cover, means connected to the shaft whereby as the shaft oscillates the arms may be alternately raised, and means for causing the depression of one arm when the other 90 is raised, said means permitting less than a full downward stroke of the arm to be depressed upon a full upward stroke of the arm to be raised.

6. In a washing machine, a tub, a cover, 95 an oscillatable driving shaft mounted above the cover and supported upon the same, a pair of arms operatively mounted upon the driving shaft above the cover for independent movement relative to each other and the 100 driving shaft, a pair of arms operatively mounted upon the cover below the same for independent movement relative to each other, plungers connected to the outer ends of both pairs of arms and extending through the 105 cover, means operatively engaging the driving shaft with the upper pair of arms to oscillate the same, and a housing detachably mounted upon the cover and extending over the upper pair of arms. 110

7. In a washing machine, a tub, a cover, a supporting frame for the tub, an oscillatable shaft section mounted upon the supporting frame, plungers carried upon the cover and extending into the tub, a plunger operating mechanism including a shaft section mounted upon the cover and adapted when the cover is lowered to operatively engage the first named section and when the cover is raised to disengage therefrom. 115

8. In a washing machine, a tub, a cover adapted to close the upper end of the tub, a housing detachably mounted upon the top of the cover, an actuating shaft entering the housing, oppositely directed arms operatively 125 connected to the actuating shaft and disposed within the housing, plunger rods connected to the outer ends of said arms and

- extending downward through said cover, and a pair of arms pivotally mounted below the cover and connected to said plunger rods, and upwardly tapering plungers mounted 5 upon the lower ends of the plunger rods.
9. In a washing machine, a tub, a supporting framework therefor, an arm hinged to the supporting framework and extending over the cover and attached thereto, plungers 10 mounted in the cover and extending into the tub, an operating mechanism for said plungers including a shaft section mounted upon the frame, a shaft section carried by said arm, the two shaft sections having operative 15 engagement with each other when the arm and cover are lowered and becoming operatively disconnected from each other when the cover and arm are raised.
10. In a washing machine, a tub, a supporting framework therefor, an arm hinged to the supporting framework and extending over the cover and attached thereto, plungers 20 mounted in the cover and extending into the tub, an operating mechanism for said plungers including a shaft section mounted upon the frame, a shaft section carried by said arm, the two shaft sections having one a clutch face and the other a sliding clutch member having a clutch face, and a spring 25 urging said sliding clutch member outward against the other clutch face.
11. In a washing machine, a tub, a cover therefor, a supporting frame for the tub, a hollow arm hinged to the supporting frame and attached to the cover, an oscillatable 30 shaft section mounted upon the supporting frame, power operated means for oscillating said shaft section, a shaft section mounted within the hollow arm, plungers having plunger rods extending through the cover, 35 means connected to the shaft section carried by the arm whereby the plunger rods may be reciprocated, said last named shaft section having a clutch face, and a clutch member 40 slidably mounted upon the first named shaft section and having a coacting clutch face, and a spring urging said clutch member toward the second named shaft section.
12. In a washing machine, a supporting frame, a tub rotatably mounted thereon, a cover therefor held from rotation, a driving shaft, means adapted to be operated by the driving shaft for rotating the tub, plungers operating through the cover, means adapted 45 to be connected to the driving shaft for operating the plungers, and means for disconnecting the tub operating and plunger operating mechanism from said driving shaft or connecting it therewith.

In testimony whereof I hereunto affix my 50 signature.

EUGENE F. BEEBE.
